UNITED STATES PATENT OFFICE.

THOMAS MAHER, OF MOUNT CLEMENS, MICHIGAN.

GAME BOARD.

1,416,107.

Specification of Letters Patent. Patented May 16, 1922.

Application filed February 24, 1919. Serial No. 278,666.

To all whom it may concern:

Be it known that I, THOMAS MAHER, a citizen of the United States of America, residing at Mount Clemens, in the county of 5 Macomb and State of Michigan, have invented certain new and useful Improvements in Game Boards, of which the following is a specification, reference being had therein to the accompanying drawings.

10 This invention relates to an improved game board of the type known as pool tables, and its object is to improve and amplify the game of pool by combining with a pool table certain structural features and with these 15 and other ends in view the invention consists in the matters hereinafter set forth and more particularly pointed out in the appended claim, reference being had to the accompanying drawings in which—

20 Figure 1 is a plan view of a game board embodying features of the invention; and

Fig. 2 is a transverse vertical section of the same substantially upon the line X—X of Fig. 1.

25 As shown in the drawings 1 indicates a board or table similar to a pool table having a wall or cushion 2 along its four marginal edges and openings 3 at each corner and intermediate the ends at each side. Pockets 30 4 are provided at the several openings 3 to receive the balls 5 and 6 which are played upon the plane field of the board or table in the usual manner, of playing pool. At one end of the board a plurality of numbered 35 field pockets or holes 7 are formed therein, these field pockets being arranged in a plurality of transverse rows with the pockets of one row in staggered relation to those of adjacent rows. The marginal wall 8 of each 40 field pocket or hole 4 is inclined inwardly from the surface of the board toward the bottom of the pocket so that the balls will roll out of the pockets readily.

In playing the game, the object balls 5 45 which are all numbered, are first racked in the usual manner near the end of the table opposite that at which the holes 7 are located. The player then breaks in the usual manner of playing pool by means of the cue

ball 6 and those object balls which fall into 50 the field pockets 7, count for the player. The object balls which remain on the table are live balls and may be driven into the field pockets by the next player. As the object balls are all numbered and also the field 55 pockets, an object ball played into a field pocket counts the player according to the number on the ball and the field pocket into which it is played, this being governed by the rules of the game. 60

If the cue ball goes off the board or into a side pocket, then the object ball does not count to the player who has played it into a field pocket.

By thus providing a pool table with a plurality of numbered field pockets or holes, a game may be played in which there is a large element of chance, and various games may be played upon the same board or the game of pool varied to give variety. 65

Having thus fully described my invention what I claim is:—

A game board of rectangular form in plan view with a plane, unobstructed surface from end to end and provided with transverse rows of cup-shaped pockets in said surface adjacent one end of the board, the pockets of each row being in staggered relation to the pockets of adjacent rows, and each pocket being of semi-circular form in 75 cross-section to receive balls rolled over said surface and to hold said balls with a major portion of the balls projecting above the plane of said surface of the board, marginal 80 side and end walls for the board forming 85 cushions, having an opening at each corner of the board and openings intermediate the ends of the side walls, pockets for all of said openings in such marginal walls, and balls to be played upon the surface of the board 90 into the pockets in said surface.

In testimony whereof I affix my signature in the presence of two witnesses.

THOMAS MAHER.

Witnesses:

LOUIS W. PINGEL,
ROBERT A. DONALDSON.
